CLAIM

The ornamental design for a combined reusable cake cover and candle holder, as shown and described.

DESCRIPTION

FIG. 1 illustrates a front right-side perspective view of a combined reusable cake cover and candle holder;

FIG. 2 illustrates a front view thereof;

FIG. 3 illustrates a rear view thereof;

FIG. 4 illustrates a top view thereof; and,

FIG. 5 illustrates a bottom view thereof.

The left-side view and right-side views of the combined reusable cake cover and candle holder are mirror images of the front view.

1 Claim, 5 Drawing Sheets
